UNITED STATES PATENT OFFICE

FRED SWAN, OF WICHITA, KANSAS, ASSIGNOR TO THE BRIDGEPORT MACHINE COMPANY, OF WICHITA, KANSAS, A CORPORATION OF DELAWARE

UNDERREAMER

Application filed January 8, 1929. Serial No. 331,140.

This invention relates to underreamers and the primary object thereof is to provide an efficient, simple construction of underreamer in which expanding and contracting cutters 5 can be expeditiously applied to the stock or head and easily removed when it is necessary to repair or redress them. The cutters are adapted to ride upon an expander due to a spring responsive actuating rod which is connected to the reins of the cutters by a cross-bar of novel construction. The cross-bar is an important feature of the invention because it permits convenient removal of the cutters whenever it is necessary to repair or redress them and it also permits the reins to be operatively associated with the actuating rod when they are to be assembled with the head or stock.

The novelty of the invention will be apparent by reference to the following description in connection with the accompanying drawings in which:

Fig. 1 is an elevational view of an underreamer constructed in accordance with my invention.

Fig. 2 is a sectional view through part of a well casing showing the head or stock, the actuating rod, the cutters and expander, parts being in elevation, parts in section and certain 30 of the parts being broken away to better illustrate certain other parts, the cutters being shown as in contracted positions.

Fig. 3 is a like view showing the cutters in expanded positions.

Fig. 4 is a detailed perspective view of one of the cutters.

Fig. 5 is an end view of the underreamer.

Fig. 6 is an enlarged view of the cross-bar.

Fig. 7 is a bottom view of the cross-bar.

Fig. 8 is an enlarged cross-sectional view 40 showing the cross-bar in elevation and the reins in section.

Fig. 9 is an end view of the reins showing the cross-bar in section and

Fig. 10 is a perspective view of a drift key.

Referring now to the drawings by numerals of reference, 1 designates the oil well casing. 2 is the head or stock provided with a shank 3 having a spring barrel or recess 4, the lower 50 end of which is constructed as at 5 to provide

a seat for one end of the coil spring 6, the opposite end bearing against the enlargement or head 7 of the cutter actuated rod 8 also in the recess 4. The lower end of the rod 8 projects below the seat and has a slotted head 55 or loop 9 to receive the cross-bar 10. The cross-bar passes through a slot in the head and it carries the reins of the cutters 11 and 12 as will be presently explained. The head 3 carries a depending expander or tongue 13 of less width than that of the head so that shoulders 14 and 15 are formed to act as stops to limit the sliding movement of the cutters in one direction. Each cutter consists of a cutting head 14' having a curved face 15' 60 to cut away the earth below the bottom of the casing or pipe 1 and each cutter is provided with arms or reins 16 and 17 provided at their upper ends with slots 18 and 19 through which the cross-bar is adapted to pass. The 70 cross-bar consists of a substantially rectangular member having upstanding end projections 20 and 21 and an intermediate upstanding projection 22 in spaced relation with the projections 20 and 21. On one face 75 of the rectangular block or member 10 are two grooves or kerfs 23 and 24 to receive the reins of one of the cutters for example, the cutter 11 and on the opposite face of the rectangular bar or block are similar grooves 80 or kerfs 25 and 26 to receive the reins of the other cutter, for example, the cutter 12. These kerfs increase in depth from the top to the bottom, from zero thickness to an appreciable depth so that the edges of the reins 85 will be retained in the grooves or kerfs during the expanding operation of the cutters as well as when expanded. The cutters are interchangeable since they are duplicates one of the other and their ends overlap as shown 90 in Figure 5. The widths of the kerfs or grooves are substantially equal to the thicknesses of the reins but the edges of the kerfs or grooves are slightly beveled as indicated at 27 to provide a relief so that the reins will 95 easily move into the kerfs or grooves when the cross-bar is inserted in the slots 18 and 19 and in the slot 28 of the headed portion 9. The ends of the cross-bar are beveled as at 29 and 30 to provide pilots to assist in guid- 100

ing the cross-bar into the slots. The inner faces of the projections 20 and 21 are also slightly beveled as indicated at 31 and 32 to guide the reins into the space between the 5 projections 20 and 21 and the intermediate projection 22.

It will be observed that the actuating rod 8 is provided with an intermediate enlarged portion 33 provided with a slot 34. This 10 slot is adapted to receive a dent or drift key 35 (see Fig. 10, Sheet 1) when the cutters are in collapsed position as shown in Figure 2 so that the cutters can be held against expanding when they are being set in the casing. A shearable pin 36 can pass through openings 37 and 38 in the cutters 11 and 12 to hold them collapsed prior to being set 15 and in order to collapse them, they can be held between the hook-shaped members 39 20 and 40 fast to the eye 41 on the floor. The head is provided with relief ports 44 and 45 (see Figure 3).

When it is desired to connect the cutters to the head, the actuating rod will be pulled 25 down and held against the expansive force of the spring by the drift key 35. Then, the reins of the cutters can be caused to straddle the head and the cross bar 10, inserted through the slots 18, 19 and 28 so that the reins will 30 drop in the kerfs provided to receive them. The cutters can be retracted and held by the drift key 35 so that the pin 36 can be inserted. Then, the drift key 35 can be removed and the 35 underreamer against the bottom of the well will break the pin 36, allowing the spring 4 to impart an upward movement to the actuating rod causing the cutters to ride on the expander tongue 13 and move into expanded and cutting position shown in Figure 3. After the cutting operation has been 40 completed, an upward pull on the head will cause the shoulders 42 and 43 to contact with the lower end of the casing causing the spring to be contracted, permitting the expanded 45 tongue upward relative to the cutters and thereby permit the cutters to retract within the casing so that the underreamer can be removed.

In Figure 5 I have shown that the reins 50 of the cutters alternately overlap. This enables the manufacturer to standardize the cutters so that they are interchangeable. This is an important feature as it reduces the number of cutters required around an oil field.

It will be apparent that the device is simple in construction, rugged and that the cutters can be easily assembled and disassembled with respect to the head or stock.

It will be apparent from the drawings that the slot 28 is longer than the width of the cross-bar 10 so that there can be enough play of the cross-bar in the slot 28 to take the tension off the spring 4 when the shoulders 42

and 43 abut against the stop shoulders 14 and 15.

What I claim and desire to secure by Letters Patent is:—

1. An underreamer comprising a slotted head, cutters having slotted reins and a cross-bar insertable through the slot in the head and through the slotted reins, the cross-bar having side and edge grooves to receive the 70 edges of the slots in the reins. 75

2. An underreamer comprising a slotted head, cutters having slotted reins and a cross-bar insertable through the slot in the head and through the slotted reins, the cross-bar having side and edge grooves to receive the 80 edges of the slots in the reins, the grooves being of varying depths.

3. An underreamer comprising a slotted head, cutters having slotted reins and a cross-bar insertable through the slot in the head and through the slotted reins, the cross-bar having side and edge grooves to receive the 85 edges of the slots in the reins, the side grooves being of progressively increasing depths 90 across the bar.

4. An underreamer comprising a slotted head, an expander tongue depending from the head, cutters having slotted reins straddling the tongue and a cross-bar for connecting the reins to the head insertable 95 through the several slots and provided with staggered grooved portions on its sides, the widths of the grooves being substantially equal to the thicknesses of the reins.

5. An underreamer comprising a slotted head, an expander tongue depending from the head, cutters having slotted reins straddling the tongue and a cross-bar for connecting the reins to the head insertable through the several slots and provided with grooved portions 105 on its side, the widths of the grooves being substantially equal to the thicknesses of the reins, the edges being beveled outwardly.

6. An underreamer comprising a slotted head having a hollow shank, a spring seated against one end of the hollow portion of the shank, an actuator rod in the shank projecting below the same and having a spring seat against which the other end of the spring rests, a slotted portion on the actuator rod normally in the shank but projectable through the shank to receive a key to hold the spring compressed, a slotted end on the actuator rod, an expander tongue on the head, cutters having slotted reins to align with the slot in the end of the actuator rod and the slot in the head, and a cross-bar projectable through the several slots, the cross-bar having grooves to receive the edges of the slots of the reins. 110 115 120 125

7. A cross-bar for underreamers comprising a substantially rectangular member having grooves of progressively increasing depths on opposite faces of the member in staggered relation. 130

8. A cross-bar for underreamers comprising a substantially rectangular member having grooves of progressively increasing depths on opposite faces of the member in staggered relation, upwardly extending end projections on the bar and an intermediate projection spaced from the end projections.

9. A cross-bar for underreamers comprising a substantially rectangular member having grooves of progressively increasing depths on opposite faces of the member in staggered relation, upwardly extending end projections on the bar and an intermediate projection spaced from the end projections, the inner faces of the end projections being beveled outwardly.

10. A cross-bar for underreamers comprising a substantially rectangular member having grooves of progressively increasing depths on opposite faces of the member in staggered relation, upwardly extending end projections on the bar and an intermediate projection spaced from the end projections, the inner faces of the end projections being beveled outwardly, the ends of the bar being beveled to provide pilot guides for inserting the bar through a slot or slots.

11. An underreamer comprising a slotted head, a slotted spring responsive cutter actuator carried by the head, cutters having slotted reins arranged in pairs to straddle the head, a cross-bar insertable through the several slots having grooves on its opposite faces to receive the edges of the grooves of the reins and a cutter expander tongue over which the cutters ride when actuated by the rod to move their cutting portions outwardly.

12. An underreamer comprising a slotted head, a slotted spring responsive actuator carried by the head, cutters having slotted reins arranged in pairs to straddle the head, a cross-bar insertable through the several slots having grooves on its opposite face to receive the edges of the grooves of the reins, the slot in the actuator being longer than the width of the cross-bar and means for moving the cutters outwardly into cutting position.

In testimony whereof I affix my signature.
FRED SWAN.
